NATIONAL CARBON COMPANY, INC., OF NEW YORK, N. Y., A CORPORATION OF NEW
YORK.

MACHINE FOR MAKING BOBBINS FOR ELECTRIC BATTERIES.

1,321,829.

Specification of Letters Patent.

Patented Nov. 18, 1919.

Application filed January 10, 1918. Serial No. 211,172.

To all whom it may concern:

Be it known that we, ABRAHAM KIPNISS and MAX PAUL NEUMANN, citizens of the United States, residing in the borough of 5 Queens, in the county of Queens and State of New York, have invented certain new and useful Improvements in Machines for Making Bobbins for Electric Batteries, of which the following is a specification, reference being had therein to the accompanying drawings, forming part thereof.

Our invention relates to machines for automatically making the inner electrodes or bobbins of usual dry batteries. Such an 15 electrode or bobbin commonly includes a cylindrically shaped mass of depolarizing material which surrounds a central electrode rod of carbon which projects therefrom at one end thereof. The machine of our present invention is a further development of 20 and improvement upon that disclosed in our copending application for patent, Serial No. 194,174, filed October 1, 1917, for machine for making bobbins for electric batteries.

25 Objects of our present invention are to simplify the construction and increase the effectiveness of the machine, and also to improve the quality and uniformity of the bobbins produced thereby. Other objects and 30 advantages of our invention will hereinafter appear.

In our above noted earlier machine the carbon electrode rod was pushed into a perforated cylinder of depolarizing material in 35 a mold, and was pushed against a solid or imperforate base plate or bottom-forming backing plate, thereby requiring, as there provided, resiliently yielding means for pushing this carbon rod into place, because 40 of the brittle and comparatively friable nature of this rod, and also introducing uncertainty as to the extent to which the carbon electrode rod would be pushed into the cylindrical perforated charge of depolarizing material, thereby causing irregularity in the 45 length of the completed bobbins, particularly in view of the fact that the carbon electrode rods, although all supposed to be of the same length, as a matter of fact exhibit considerable inequality in length. As a feature 50 of our present invention, and in clear differentiation from our above noted prior invention, means are provided for inserting the carbon rod into the mold and into the depolarizing material therein at one end there-

of and for forcing or pushing this carbon electrode rod completely through the mold and through the charge of depolarizing material contained therein until such rod projects from the other or opposite end of the 60 mold and of the material contained therein, and until such rod is substantially flush with the end of the charge at which such rod was introduced, thereby effectively assuring that such electrode rod extends throughout the 65 length of the cylindrical charge of depolarizing material, and also entirely eliminating any liability whatever of breaking this electrode rod by reason of excessive endwise pressure thereupon. Our invention also 70 more particularly includes various features of construction and combinations of parts and sub-combinations thereof as will appear from the following description.

We shall now describe the automatic bobbin making machine embodying our invention illustrated in the accompanying drawings and shall thereafter point out our invention in claims.

Figure 1 is a front elevation of an automatic bobbin making machine embodying our invention, the machine being shown with its parts in the position in which they automatically come to rest when the machine is not in operation.

Fig. 2 is a side elevation as viewed from the right in Fig. 1 and with parts omitted.

Fig. 3 is an enlarged horizontal and transverse section on a plane indicated by the line 3—3 of Fig. 1 as viewed from above, with 90 parts omitted, and illustrating a slightly different and succeeding phase of operation in which a mold-carrying turret has reached its position of rest with the molds carried thereby in alinement with a series of plungers.

Fig. 4 is a partial vertical section on planes indicated by the offset line 4—4 of Fig. 3 as viewed from below.

Fig. 5 is a similar section on planes indicated by the offset line 5—5 of Fig. 3, and 100 which at the left coincides with the line 4—4.

Fig. 6 is a partial vertical section on planes indicated by the offset line 6—6 of Fig. 3 as viewed from the left.

Fig. 7 is a similar view on the offset line 105 7—7 as viewed from the left, and which in its lower part coincides with the line 6—6.

Fig. 8 is a partial vertical section on a plane indicated by the line 8—8 of Fig. 3 as viewed from below.

Fig. 9 is a view similar to Fig. 8 but with the movable parts in a different and succeeding position.

Fig. 10 is a partial transverse or horizontal 5 section on a plane indicated by the line 10—10 of Fig. 9 as viewed from above.

In the automatic electrode making or bobbin making machine embodying our invention illustrated in the accompanying drawings, the usually somewhat moist powdered depolarizing material is adapted to be contained in a main supply magazine 1 which in its lower part at one side thereof freely 10 communicates with a smaller auxiliary magazine or feed magazine 2. A rotating stirrer shown as comprising wings or paddles 3 carried by a head 4 mounted upon a vertical rotating shaft 5, prevents packing of the fine moist depolarizing powder in the main 15 magazine 1, and also assists its flow therefrom into the smaller feed magazine 2, as will be readily understood. A similar smaller stirrer in the feed magazine 2 has stirring blades 6 carried by a head 7 mounted 20 upon a vertical operating shaft 8.

The stirrer blades 6, together with gravity, cause the powdered depolarizing material to enter the open upper ends of a series, shown as sixteen in number, of vertically arranged molds 9 carried by a horizontally arranged rotating turret 10 shown as provided with an upper plate or face plate 11 which forms a bottom for the feed magazine 2 and upon which the powdered depolarizing material therein rests, and in the construction shown in the drawings, the upper open ends of a plurality of an average of four of the molds 9 are in communication with the feed magazine 2, as appears most 30 clearly in Fig. 3 of the drawings. The machine has a horizontally arranged bed plate 12 shown as provided on its upper side with a base plate 13 which closes the lower ends of and forms a bottom for the powder-receiving molds 9, as clearly appears 35 in the drawings. By reason of gravity and the stirring blades 6, the molds 9 become evenly filled with loose depolarizing powder in the form of a cylinder 14, as appears 40 in the drawings at the left in Figs. 4 and 5 more particularly. The turret 10 is fixed upon the upper end of a vertical operating shaft 15 shown as extending down through the bed plate 12 and as mounted in bearings 45 carried thereby, these bearings for the turret shaft 15 including a weight-supporting thrust bearing shown as a ball bearing.

The mold-carrying turret 10 is automatically periodically rotated step by step or intermittently a distance equal to the space 50 between the equidistantly spaced mold 9 by means now to be described. A short transverse or horizontal operating shaft 16 journaled in the frame of the machine at its inner end is connected to the turret shaft 15 to

rotate the latter at the same rate of speed by means of a pair of similar bevel gears 17. At its outer end the turret-operating shaft 16 has fixed thereon a ratchet wheel 18 which has sixteen equidistantly spaced peripheral 70 ratchet teeth corresponding to the sixteen equidistantly spaced molds 9 of the turret 10. A vertically arranged rocking lever 19 pivoted on the operating shaft 16 carries at its lower end a spring-pressed pivoted pawl 75 20 pressed to engaging position by a spring 20^a and which engages the ratchet teeth of the ratchet wheel 18, and at its upper end the rocking lever 19 has pivoted thereto one end of an operating link 21 which extends 80 rearwardly and is shown as provided with a slot by which it is guided on a rotating cam shaft 22 which is journaled in the lower part of the frame of the machine and extends parallel with the turret-operating 85 shaft 16. The adjacent end of the cam shaft 22 carries a sector-shaped cam 23 which as the cam shaft 22 rotates engages a rear cam roller 24 on the rear end of the operating link 21 for thereby imparting 90 rearward turret-rotating movement to the operating link 21, and which also engages another or forward cam roller 25 on the operating link 21 for moving this link forward thereby to retract the turret-operating 95 pawl 20 over one of the ratchet teeth of the ratchet wheel 18, the proportions and arrangement of the turret-operating cam 23 being such that the ratchet wheel 18 will be moved up one tooth and then have a period 100 of rest for each rotation of the turret-operating cam shaft 22 and whereby the mold-carrying turret 10 will have a corresponding movement with intervening periods of rest, as will be readily understood. During 105 the operation of the machine the cam shaft 22 is continuously rotated from and at the same rate of speed as a main shaft or crank-shaft 26 which is journaled transversely in the upper part of the frame of the machine 110 parallel with the cam shaft 22 and is connected thereto by means of a pair of similar sprocket wheels 27 and a sprocket chain 28.

A plunger-carrying cross-head 29 is vertically slidable in guideways provided in the frame of the machine, and during the operation of the machine is continuously reciprocated by means of a two-part connecting rod 30 and crank 31 on the main shaft 26, the connecting rod 30 being shown as adjustable as to its length by means of a turn-buckle 32 which forms a coupling between the two parts of this connecting rod. Before proceeding further it may be as well to note that the hereinbefore described stirrer in the main magazine 1 is continuously rotated during the operation of the machine by means of a bevel gear 33 fixed upon the upper end of the stirrer shaft 5 and engaged by a bevel pinion 34 carried by a short trans- 130

verse shaft 35 which is geared to the main shaft 26 by means of a pair of similar spur gears 36, as clearly appears in the drawings. Also it is as well to note in this connection 5 that the hereinbefore described smaller stirrer in the feed magazine 2 is rotated alternately in opposite directions during the operation of the machine by means of a rack 37 carried by the cross-head 29 at the front 10 of the machine and engaging a spur gear 38 which is an idler and meshes with a spur pinion 39 fixed upon the outer end of a short rearwardly extending shaft 40 which at its rear end is geared to the stirrer shaft 8 by 15 means of a pair of similar bevel gears 41, as is clearly shown in the drawings.

Locking means, shown as movable abutment means, are provided for preventing the continued rotation of the mold-carrying 20 turret 10 under its own momentum after it has ceased to be actuated by the periodically acting means hereinbefore described and including the ratchet wheel 18 and its intermittently acting operating means. The 25 mold-carrying turret 10 is shown as provided with a peripheral series of sixteen equidistantly spaced radially projecting abutment studs 42 corresponding to the sixteen equidistantly spaced molds 9 carried by 30 this turret. At the rear of the turret 10 a forwardly extending abutment finger 43 is normally in position to engage one of the abutment studs 42. This abutment finger 43 is carried by the lower end of a vertically 35 arranged pivoted actuating lever 44 to the upper arm of which is connected a retractile spring 45 for moving the abutment finger 43 to its stud-engaging position. At its upper end and at the rear the finger-actuating 40 lever 44 is shown as slightly tapered or rounded so as to provide a cam surface which is adapted to be engaged by an L-shaped actuating member 46 carried by the plunger-carrying cross-head 29 at the rear 45 thereof, and upon the descent of the cross-head this actuating member 46 operates the lever 44 to retract the abutment finger 43 out of the path of the peripherally projecting abutment studs 42. When the abut- 50 ment finger 43 is retracted, a laterally extending retractile spring 46^a connected thereto and anchored to the frame of the machine operates to shift this lever to the right as viewed from the front of the machine 55 and as seen in Fig. 3, so that when the plunger-carrying cross-head 29 descends and while the turret 10 is still stationary, the forward lug-engaging end of this abutment finger 43 will be shifted to the extent per- 60 mitted by a certain amount of lost motion in the pivoted operating lever 44 sufficiently so that the forward end of the abutment finger 43 under the actuation of the spring 46^a will rest upon the top of 65 the abutment stud 42 which it before was in

engagement with, thereby leaving the turret 10 free to be rotated when its operating mechanism hereinbefore described is brought into operation as provided for in the construction of the machine and whereupon 70 the spring-pressed abutment finger 43 upon the next intermittent partial rotation of the mold-carrying turret 10 will be free to be pressed into its engaging position by the spring 45, as will be readily understood, 75 thereby effectively preventing the momentum of the turret 10 and its connected parts from carrying it too far.

The means for forming the loose cylindrical charges 14 contained in the molds 9 80 into firmly compacted bobbins having an electrode rod extending therethrough and projecting from one end thereof and including features of our present invention will now be described. The cross-head 29 rigidly 85 carries four downwardly projecting plungers for operating upon the cylindrical charges 14 of loose depolarizing material contained in the molds 9 at the successive periods of rest of the intermittently rotated 90 turret 10, all of these four plungers, how- 95 ever, being operated at once and each performing its own operation different from that of any of the other plungers and in a different mold, the molds being moved successively into alignment with the successive plungers. In the particular machine illus- 100 trated in the drawings the four plungers, which are arranged in an arcuate series, are spaced apart twice the distance of the spacing between the molds 9, so that as the mold-carrying turret 10 rotates there will at all times in the operation of the machine be a mold 9 in an inactive or non-operative position of rest between the plungers when they are actuated, as is indicated in Fig. 3, so that in this machine the plungers operate upon the charges of depolarizing material in each alternate mold 9 with- 105 out, however, thereby in any particular in- 110 terfering with the final result, as will be readily understood.

The first of these plungers is a combined compressing and punching plunger comprising a shank 47 which is fixed in the cross-head 29, and a downwardly extending compressing part 48 which is cylindrical and adapted to snugly enter any one of the molds 9 and from the center of which there projects a punching rod or tip 49. The length 115 or extent of the downward projection of the compressing part 48 of this plunger is such that upon the descent of the plunger-carrying cross-head 29, the loose charge 14 in the mold 9 which has been brought into 120 a position of rest below and in alignment with this plunger will be compressed to the desired extent, and the length or extent of downward projection of the punching rod 49 is such that concurrently with this com- 125 130

pression the charge of depolarizing material will have a hole punched therein by the downward movement of this punching tip 49, part way through the charge in the 5 mold 9 but not all of the way through to the bottom-forming face plate 13 which overlies the bed plate 12, and in the lowered position of the punching tip 49 there will be a space between its lower end and the 10 upper surface of the face plate 13. At this operation of compressing and punching the loose cylindrical charge 14 which appears at the right in Fig. 4 beneath this combined compressing and punching plunger will be 15 compressed and a hole punched therein to form the tube 50 of depolarizing material which appears at the right in Fig. 5 where this punched or partly perforated cylinder 50 in the intermittent rotation of the 20 turret 10 is in position for the next succeeding operation after the completion of the operation of compressing and punching just described. This arrangement for punching a hole part way only through the charge 25 forms a feature of our present invention, as differentiated from our above noted prior invention.

The second plunger to operate is a carbon-inserting plunger for inserting a carbon electrode rod into the hole in the cylinder 50, and this plunger comprises an enlarged securing shank 51 fixed in the cross-head 29 and a downwardly projecting carbon-inserting rod 52 for pushing a carbon 30 electrode rod 53 downward into the upper end of the compressed and partly perforated cylindrical charge 50, as appears at the right in Fig. 5, this carbon electrode rod 53 having been brought into vertical position in alinement with the inserting rod 52 and the hole in the punched charge 50 by means which will presently be described. In the particular machine illustrated in the drawings, the carbon electrode rod 53 is not pushed 35 or forced all of the way through the cylinder 50 by the carbon-inserting rod 52, but the proportions and extent of movement of the parts are such that this rod is pushed all of the way into the mold 9 until its upper end is level or flush therewith, but by 40 reason of the originally greater length and previous compression of the charge 50, the carbon electrode rod 53 is pushed only part way into and part way through the cylindrical charge 50, and will be held in the upper end of the hole in the upper end thereof, as appears at the left in Fig. 6 and at the right in Fig. 8 illustrating the completion 45 of the operation indicated at the right in Fig. 5 in one of the molds 9 which has been carried to the next succeeding position for an operation of the next succeeding plunger, but before this third operation has been performed. This partial insertion of the 50 carbon rod 53 in the punched cylinder 50

forms one of the features of our present invention, differentiating it from our above noted prior invention. If an attempt were made, as heretofore and as in our above noted prior machine, to push this electrode 70 rod 53 all of the way through the punched cylinder 50, the depolarizing material left at the bottom thereof together with other scraped off by the advancing end of the electrode rod would interfere with the complete insertion of the electrode rod 53 and this carbon rod would be broken unless some special yieldable means were provided, such as was done in our above noted prior machine, and also the bobbin would be imperfect by reason of the fact that the carbon electrode rod 53, not extending so far into the depolarizing material, would not be so fully exposed to its action, and also the additional projection of the carbon rod 85 from the cell would be objectionable and would interfere with the use of these cells, particularly as commonly assembled to form batteries.

The next or third plunger to act is a combined carbon-positioning and compressing plunger which has a shank 54 fixed in the cross-head 29, and a working tip 55 which is cylindrical and of a size to fit snugly within any one of the cylindrical molds 9. 90 When the plunger-carrying cross-head 29 descends, the cylindrical plunger tip 55 will enter the mold 9 which has been brought to a position of rest in alinement therewith as appears at the left in Fig. 6 and at the right in Fig. 8, the mold 9 being thus brought to rest before this plunger has descended more than to a very slight extent and as is indicated by the position of the crank 31 in the upper part of Fig. 6. As the cross-head 29 descends the plunger tip 55 will first engage 100 the outer or upper end of the carbon electrode rod 53 which as appears in the drawings and as hereinbefore noted projects from and above the upper end of the compressed and punched or partly perforated charge 50 of depolarizing material and is substantially flush with the top of the face plate 11 of the mold-carrying turret 10, and the plunger tip 55 as it descends pushes this 105 carbon electrode rod 53 downward into the tubular upper end of the charge 50 of depolarizing material until the lower end of the plunger tip 55 comes in contact with the upper end of the initially compressed and 110 partly perforated cylindrical charge 50 of depolarizing material, after which the further descent of the plunger tip 55 not only moves the carbon rod downward but also further and finally compresses the depolarizing material around this carbon rod 53, thereby to produce a firmly compressed tube 115 56 of depolarizing material around the carbon rod 53, which by reason of its greater length projects downward from and beyond 120 125 130

the lower end of this finally compressed tube 56, as is shown at the right in Fig. 9 and at the left in Figs. 7 and 8. It is to be noted that toward the latter part of its 5 movement the descending carbon rod 53 acts as a perforating punch for punching out the depolarizing material which was left at the bottom of the hole formed by the punch 49. In view of the fact that the carbon elec- 10 trode rod 53 is pushed entirely through the cylinder 50 of depolarizing material from the upper end thereof until it projects from the lower end thereof, it will be readily understood that the carbon electrode rod 53 15 will extend entirely through this charge 50 with its upper end, when in the inverted position in the machine as shown in the drawings, flush with the upper end of the finally compressed tube 56 and with its 20 lower end projecting therefrom, thereby eliminating the possibility of irregularity in the positioning of the carbon rod within in the depolarizing material in the completed battery cell.

25 In order to provide for the reception of the downwardly projecting lower end of the carbon electrode rod 53, and for the further rotation of the mold-carrying turret 10 to the position at which the completed elec- 30 trode bobbin is discharged or ejected from the mold 9, means are provided now to be described. The bed plate 12 of the machine is provided with an elongated slot 57 and immediately above the slot 57 in the bed 35 plate 12 the overlying face plate 13 is provided with a tapered slot 58, the smaller end of which, appearing at the right in Figs. 8, 9, and 10, is just of a size to permit the free passage of the lower projecting end of 40 the electrode rod 53, and is shown as cylindrically rounded to correspond with the circumferential curve of the cylindrical electrode rod, while the other or larger end of the slot 58, which appears at the left in Figs. 45 8, 9 and 10, is circularly curved and is of sufficient width for the free passage of the completed electrode including the tube 56 thereof, for thereby permitting the discharge of the completed bobbins from the 50 molds 9 in the ejecting operation performed by the fourth and last plunger, as will presently appear.

It will be noted that in the two preceding or first and second operations the face plate 55 13 forms an imperforate bottom for the molds 9, the first operation referred to being the initial compression and punching or partial perforation of the loose uncom- 60 pressed and unpunched charge 14 of de- polarizing material to form the initially compressed and punched charge 50, and this operation being performed by the first plunger having the shank 47, and having the compressing part 48, and punching tip 49, 65 and the second operation referred to being the insertion of the carbon electrode rod 50 by the second plunger having the carbon-inserting rod 52. It is now to be noted that at the third operation just described of positioning the carbon electrode rod 53 within 70 the initially compressed and punched charge 50 and further finally compressing this charge 50 to form the bobbin tube 56, the face plate 13 forms a partial bottom for the molds 9 in this position, and supports the 75 charge 50 during the positioning of the electrode rod 53 and the final compression of this charge 50 at all points excepting in the space occupied by the smaller end of the tapered slot 58; and movable abutment 80 means now to be described are provided for intermittently closing the smaller end of this slot beneath the charge of depolarizing material and leaving only an opening or hole at the smaller end of the slot 58 for the passage 85 of the lower end of the electrode rod 53. A movable abutment 59 is shaped in tapered form at its upper end for closing the smaller end of the tapered slot 58, excepting to leave a hole in the end of this slot for the passage 90 of the carbon electrode rod 53. This movable abutment 59 is carried by a laterally extending lever arm 60 shown as formed in one piece or integral therewith, and pivoted to the frame of the machine at the lower 95 side of the bed plate 12 on a pivot pin 61, as appears most clearly in Figs. 8 and 9. In its upper or elevated position the abutment 59 co-operates with the face plate 13 to form a complete bottom for the mold 9 beneath 100 the final compressing and carbon-positioning plunger tip 55, as appears at the right in Fig. 9 and in Fig. 10, leaving only, as above described, an opening for the downward movement of the downwardly projecting 105 rod 53. In its lowered position appearing in the other figures of the drawings, particularly in Figs. 2 and 8, the abutment member 59 has moved downward entirely clear of or out of the tapered slot 58 so as to 110 provide for the lateral movement of the downwardly projecting end of the electrode rod 53 along the slot 58 toward the larger end thereof as the turret 10 rotates. The abutment member 59 together with its lever 115 60 is adapted to be moved to its lower or non-operative position by means of gravity assisted by the downward pull of a retractile spring 62, appearing in Figs. 2 and 9, which is attached to the lever 60 and is anchored 120 to a pin 63 projecting from a part of the frame of the machine.

The abutment member 59 is adapted to be operated in proper timed relation from the cam shaft 22 by means of a lifter cam 64 125 thereon shown as of sector shape (see Fig. 2) which engages a cam roller 65 carried by a lifter arm 66 which is pivoted at its rear end at 67 (see Fig. 2) to the frame of the machine, and extends forward beneath and 130

in engagement with the abutment-carrying lever 60. The shape or contour of the abutment-operating cam 64 is such, as appears in the drawings, that the abutment member 59 will be raised and will then be held or sustained in this raised slot-closing bottom-forming position appearing in Figs. 9 and 10 for a sufficient length of time during a position of rest of the mold-carrying turret 10 for the operation of the third plunger 55, as hereinbefore described, and the shape of this cam 64 is also such as to maintain the abutment member 59 in a depressed position with the slot 58 open, as appears in the drawings, particularly in Fig. 8, during the movement of the mold-carrying turret 10, so as to permit a mold 9 having an electrode rod 53 projecting downward therefrom to move away from its position in alignment with the third plunger 55, after the operation of this plunger as above described. In view of the fact, as hereinbefore noted, that the plungers are spaced apart twice the distance of the spacing of the molds 9, it will require two successive movements of the turret 10 in order to bring the mold 9 from its position in alignment with the third plunger 55 to the position in alignment with the next or fourth plunger at the larger end of the tapered slot 58, or stated in other words, it will require two successive movements of the turret 10 to transfer a mold 9 from the smaller to the larger end of the tapered slot 58 in the bottom-forming face plate 13.

35 The condition of the uncompleted bobbin after the operation of the second or carbon-inserting plunger 52 and before the operation of the third plunger 55 appears at the left in Fig. 6 and at the right in Fig. 8, and 40 after the operation of the third plunger 55 the bobbin is then complete in the mold 9, as appears at the right in Fig. 9 and at the left in Figs. 7 and 8.

45 The fourth and last plunger to operate in the molds 9 is an ejecting plunger for discharging the completed electrode bobbins from the molds, and this plunger comprises a securing shank 68 fixed in the plunger-carrying cross-head 29, and having at its 50 lower end an ejecting tip 69 which is correspondingly longer than and projects below the carbon-positioning and final compressing tip 55 of the third plunger, the plunger tip 69 being shown in the drawings as of the 55 same length as the molds 9, and as being adapted to move downward from a position above a mold 9 in alignment therewith, until the lower end of the plunger tip 69 is flush with the lower end of the mold 9, as appears 60 at the left of Fig. 9. The larger end of the tapered slot 58 in the face plate 13 is at all times left freely open, and as the plunger tip 69 moves downward from the position above the mold 9 in alignment therewith and containing a completed electrode bobbin, as ap-

pears in the drawings, particularly at the left of Figs. 7 and 8, to the position appearing at the left of Fig. 9, the completed bobbin which appears in the mold 9 at the left of Figs. 7 and 8 will be ejected or pushed 70 downward out of the mold through the larger end of the tapered slot 58, and through the elongated slot 57, and will drop freely downward where it may be received by any means provided for the purpose or may be 75 caught in the hand of an operator, the latter being the way which has been employed in the operation of the machine shown in the drawings.

The means by which the carbon electrode 80 rods 53 are supplied and are successively brought into alignment with the carbon-inserting plunger rod 52 will be described. The carbon electrode rods 53 are contained in a magazine 70 in horizontal position and 85 descend by gravity through an inclined chute 71 which the electrode rods 53 may freely enter successively one after the other at the upper end thereof from the rod-containing magazine 70. A slotted block 72 forms a 90 continuation of the lower end of the chute 71, and a rock shaft 73 is journaled in the lower and forward part of the slotted block 72 and at its inner end, appearing at the left in Figs. 1, 3, 4, and 5, has fixed thereon 95 a carbon-alining or carbon-positioning rock-arm 74 which is provided with a carbon-receiving longitudinal groove 75, and this grooved face of the rock-arm 74 is adapted to move in contact with a vertically disposed 100 smooth flat inner face of the slotted block 72, and the rock shaft 73 is provided with an aperture 76 in alignment with the carbon-receiving slot 75 of the rock-arm 74 as clearly appears in the drawings, particularly in 105 Fig. 5 thereof. The groove 75 in the rock-arm 74 is of a depth to receive one of the carbon electrode rods 53 therein and in the normal or horizontal position of the carbon-positioning rock-arm 74, this slot 75 registers with the lower end of the inclined slot in the slotted block 72 in position to receive the lowermost of a series of the carbon rods 53 which move downward by gravity 110 through the chute 71 and slotted block 72 115 forming a continuation of the lower end of the chute, this horizontal carbon-receiving position of the rock-arm 74 appearing in the drawings in Fig. 1, and this being the position of the parts of the machine appearing 120 in Fig. 2 also.

The rock shaft 73 which carries the rock-arm 74 is adapted to be rotated through a quarter turn for thereby bringing the carbon rod 53 carried by the rock-arm 74 in the 125 groove 75 thereof into a vertical position in alignment with the carbon-inserting plunger rod 52, and also into alignment with the hole in the punched and partly compressed charge 50 in the mold 9 at the corresponding position, by 130

means of a rack bar 77 slidable in guideways provided at the side of the machine and engageable with pinion teeth 78 formed upon the outer end of the rock shaft 73, as more 5 particularly appears in Fig. 2 of the drawings. A sliding movement is imparted to the rack 77 by means of a vertically arranged operating lever 79 pivoted on the frame of the machine by a pivot stud 80. 10 At its lower end the lever 79 is connected to the forward end of the rack 77 by means of a short link 81, and the upper free end of this lever 79 carries a cam roller 82 which is engaged by an operating cam 83 fixed upon 15 the adjacent end of the crank-shaft 26, this cam 83 being so shaped as properly to operate the rock-arm 74 for bringing the carbon electrode rod 53 into alinement with and beneath the elevated carbon-inserting plunger 20 tip 52 in proper timed relation in the operation of the machine, as will be readily understood. After the alined carbon electrode rod 53 carried in the groove 75 of the rock-arm 74 has been pushed downward by the 25 descending carbon-inserting plunger tip 52 through the aperture or transverse hole 76 in the rock-shaft 73 and into the upper end of the hole in the partly or initially compressed and punched charge 50, from the 30 position of this rod appearing at the right in Fig. 5, to the position thereof appearing at the left in Fig. 6 and at the right in Fig. 8, the carbon-positioning rock-arm 74 is returned from its vertical to its horizontal 35 carbon-receiving position, and this is accomplished by means of a coiled retractile spring 84 attached to the upper arm of the vertically arranged lever 79 and anchored to the frame of the machine, as appears in the 40 drawings in Figs. 1 and 2. For holding the carbon rod 53 in position in the groove 75 of the rock-arm 74, an arcuate spring wire 85 is contained in a groove 86 in the adjacent flat face of the slotted block 72 and is anchored at its ends thereto, and exerts a slight 45 pressure on the carbon rod 53 carried by the rock-arm 74, this wire 85 appearing most clearly in Fig. 6. A stop-pin or abutment stud 87 is shown as provided on the flat 50 lateral face of the slotted block 72 for assuring that the carbon-carrying rock-arm 74 shall stop at the correct vertical position with the carbon rod 53 carried thereby in alinement with the carbon-inserting plunger 55 rod 52.

In order to prevent the carbon electrode rods 53 from escaping from the lower end of the inclined slot 88 in the slotted block 72 during the vertical or elevated position 60 of the rock-arm 74, a gate member 89 is provided for the lower end of this slot 88, and at the proper time is raised sufficiently to prevent the escape of the carbon electrode rods 53 by means of a short rocking lever 65 90 which at its inner end engages beneath

a lateral angularly extending part of the gate 89, as appears most clearly in Fig. 5 and which at its outer end is adapted to be engaged and operated by a cam member 91 carried by the slidable rack 77, as appears 70 most clearly perhaps in Fig. 6 of the drawings. When the outer end of the operating lever 90 is released by this cam member 91, the gate 89 will move downward by reason of gravity and also by reason of downward 75 movement which will be imparted thereto through a projecting stud 92 which will be engaged by the descending rock-arm 74, and which also serves as an abutment or stop for this rock-arm in its carbon-receiving position. 80

To prevent the possible clogging of the carbon electrode rods 53 within the magazine 70 at the upper end of the chute 71, a slidable agitating bar 93 is arranged along 85 the upper inclined surface of the chute 71, projecting at its upper end into the lower part of the magazine 70, and at its lower end carrying a cam block 94 having an inclined operating face which is adapted to be 90 engaged by the correspondingly inclined operating face of a cam member 95 mounted upon the rack 77, as shown in the drawings, particularly in Fig. 3.

The means for applying power to the machine for driving it will now be described. A spur driving gear 96 is loosely mounted upon the projecting outer end of the crank-shaft 26, appearing at the right in Fig. 1, and at the front in Fig. 2, and is adapted 95 to be rotatively connected to or coupled to the crank-shaft 26 by means of a suitable clutch which may be a usual one-revolution clutch and that being the kind of clutch employed in the machine illustrated in the 100 drawings, and having a vertically movable clutch-controlling member 97 shown as carried by the forward end of a pivoted lever 98 which at its rear end is pivoted upon the frame of the machine and which is adapted 105 to be raised to clutch-disengaging position by means of a coiled retractile spring 99 attached thereto and shown as anchored to the frame of the machine near the top thereof, as appears in Figs. 1 and 2 of the 110 drawings. The clutch-controlling member 97 is adapted to be depressed for connecting or coupling the driving gear 96 to the crank-shaft 26, by means of a pedal 100 connected to the controlling lever 98 by means of a 115 long link 101.

The spur driving gear 96 is continuously rotated by means of a spur pinion 102 meshing therewith and carried by the adjacent end of a transverse power shaft 103 journaled in the upper part of the frame of the machine at the rear and slightly below the crank-shaft 26, and provided at its other end, appearing at the left in Fig. 1, with a belt-receiving driving pulley 104 shown as 120 125 130

having thereon a projecting rim 105 forming a fly-wheel.

It is obvious that various modifications may be made in the construction shown in 5 the drawings and above particularly described within the principle and scope of our invention.

We claim:

1. A bobbin making machine comprising a 10 mold, means for supplying depolarizing material to the mold, means for concurrently compressing and forming a hole in the depolarizing material in the mold at a single operation, means for inserting an electrode 15 rod in the hole formed in the charge of depolarizing material, means for forcing said rod through such material until its opposite end projects therefrom and concurrently further compressing the depolarizing material 20 around the electrode rod, and means for discharging the completed bobbin from the mold.

2. A bobbin making machine comprising a mold, means for supplying depolarizing 25 material to the mold, a compressing plunger for compressing the depolarizing material in the mold, a rod fixedly projecting from the compressing end of the plunger for punching a hole in the depolarizing material 30 in the mold concurrently with the compression thereof by the plunger, a plunger for inserting an electrode rod in the hole formed in the depolarizing material in the mold, and a combined carbon-positioning and 35 compressing plunger for pushing said electrode rod along in the depolarizing material until said electrode rod projects from the opposite end thereof and for concurrently compressing the depolarizing material 40 around said electrode rod to a predetermined length.

3. A bobbin making machine having, in 45 combination, a mold, a plunger for punching a hole in depolarizing material in the mold, and a plunger for inserting an electrode rod into said hole, and a plunger for concurrently pushing the electrode rod through the depolarizing material until it projects from the opposite end thereof and 50 for compressing the depolarizing material around the electrode rod to a predetermined length.

4. A bobbin making machine comprising a series of similar molds, a series of four 55 similar plungers, means for bringing the different molds and plungers into successive alinement, means for supplying depolarizing material to the successive molds, and means for producing relative movement of the 60 alined molds and plungers for causing the plungers to operate upon the material in the molds; the first of said plungers being a combined compressing and punching plunger adapted to compress and punch a hole in 65 the material in the mold, the second of said

plungers being adapted to insert an electrode rod in the hole in the material in the mold, the third of said plungers being adapted to push the electrode rod along in the material in the mold until it projects 70 from the opposite end thereof and for concurrently compressing the material around the electrode rod to a predetermined length, and the fourth of said plungers being an ejecting plunger for discharging the completed bobbin from the mold.

5. A bobbin making machine having, in combination, a mold, means for forming in the mold a charge of depolarizing material having a longitudinal hole therein, 80 means for pushing an electrode rod into the hole in the charge of depolarizing material in the mold, means for further pushing the electrode rod along in said material until it projects from the opposite end 85 thereof, a backing member for supporting the depolarizing material while the electrode rod is pushed along therein so as to project therefrom at the opposite end thereof, and means for discharging the completed bobbin from the mold.

6. The invention claimed in claim 5 in which the means for further pushing the electrode rod along in the material in the mold includes means for further compressing the depolarizing material around the 95 electrode rod.

7. A bobbin making machine having, in combination, a mold, means for supplying depolarizing material to the mold, means for pushing an electrode rod longitudinally 100 through said material in the mold until it projects from the opposite end thereof and for compressing said material around the thus positioned electrode rod, and means for discharging the completed bobbin from 105 the mold.

8. A bobbin making machine having, in combination, a mold, means for supplying depolarizing material to the mold, a plunger 110 for inserting an electrode rod longitudinally into such material in the mold, and a plunger for pushing the electrode rod along in such material until it projects beyond the opposite end of the charge of depolarizing material in the mold and for compressing the depolarizing material in the mold around the electrode rod.

9. A bobbin making machine having, in combination, a mold, means for supplying depolarizing material to the mold, a plunger 115 for inserting an electrode rod longitudinally into such material in the mold, a plunger for pushing the electrode rod along in such material until it projects beyond the opposite end of the charge of depolarizing material in the mold, and an automatically moving movable backing member which supports the depolarizing material while the electrode rod is pushed along therein 120 125 130

so as to project therefrom at the opposite end thereof.

10. The invention claimed in claim 8 in combination with an automatically moving 5 movable backing member which supports the depolarizing material while it is compressed around the electrode rod and providing for the movement of the electrode rod to the projecting position.

11. A bobbin making machine comprising a movable carrier provided with a series of molds, means for supplying depolarizing material to the molds, backing means forming bottoms for the molds and relatively to 15 which the molds are transversely movable, means for forcing an electrode rod longitudinally through the depolarizing material in the mold and to a position projecting beyond such material and beyond the 20 bottom-forming surface of said bottom-forming backing means, said backing means being provided with a slot for receiving the projecting end of said electrode rod, and a bottom-forming backing member movable 25 into position partly to close said slot and thereby to support said depolarizing material around the projecting end of said electrode rod and movable to a position out of said slot to permit the passage laterally 30 of the projecting end of said electrode rod during said transverse shifting movement of said carrier relatively to said backing means.

12. A bobbin making machine comprising 35 a mold, means for supplying depolarizing material to the mold, a slotted backing member forming a bottom for said mold and relatively to which said mold is transversely movable, means for forcing an electrode rod longitudinally through said material to a 40 position in which it projects from the opposite end thereof into said slot, and a movable bottom-forming member adapted partly to close said slot and to support said 45 material during the movement of said electrode rod to its projecting position and adapted to be retracted to open said slot for permitting said relative transverse movement of the mold relatively to said slotted backing member.

13. A bobbin making machine comprising a rotative mold-carrying turret, means for supplying depolarizing material to the molds, a backing plate forming bottoms for the molds, means for concurrently making 55 a hole in a charge of depolarizing material in a mold and compressing it against said backing plate, means for inserting an electrode rod into said hole and pushing it along 60 in said charge until it projects at the other end thereof beyond the bottom-forming surface of said backing plate, a tapered slot being provided in said backing plate and the smaller end of which receives said electrode rod and which provides for the trans-

verse movement of said electrode rod during the rotation of said turret, and ejecting means for discharging the completed bobbin through the larger end of said tapered slot in the backing plate.

14. The invention claimed in claim 13 in combination with a movable bottom-forming member for closing the narrow end of said slot at the side of said projecting electrode rod and thereby supporting the depolarizing material during the pushing in of the electrode rod to the projecting position and adapted to move out of said slot to provide a clear passageway for the projecting end of said electrode rod in its transverse movement during the rotation of the mold-carrying turret.

15. A machine for making bobbins for electric batteries of the kind in which a rotating turret carries a series of molds containing depolarizing material which is acted upon by a series of plungers for forming an electrode bobbin in which an electrode rod projects from one end of the cylindrical mass of depolarizing material, characterized by the fact that one of these plungers pushes the electrode rod through the mold until it projects from the other end thereof and from the corresponding end of the material contained in the mold and compresses the depolarizing material in the mold around the electrode rod.

16. The invention claimed in claim 15 in combination with a backing member forming a bottom for the successive molds and 100 provided with a slot for receiving the projecting end of the electrode rod, and a movable bottom-forming abutment member for closing said slot at the side of said projecting electrode rod and movable out of said 105 slot to provide for the passage of said projecting end of the electrode rod as the mold-carrying turret rotates.

17. An automatic machine for making bobbins for electric batteries of the kind in 110 which a series of plungers are automatically reciprocated for acting upon depolarizing material contained in a series of molds carried by a relatively rotating mold-carrying turret for forming such depolarizing material into a cylinder having an electrode rod projecting from end thereof, characterized by the fact that a first plunger concurrently compresses and punches a hole in the depolarizing material in the mold, a second plunger inserts an electrode rod into such hole, a third plunger pushes this electrode rod along in the mold and along in the material contained therein toward the other side thereof and until the end of said 120 rod projects from the other end of the mold and of the material contained therein, and a fourth plunger for discharging the completed bobbin from the mold.

18. The invention claimed in claim 17 in 130

- which a backing plate provides a closure for the bottoms of the molds and has therein a tapered slot for the projection and transverse passage of the projecting end of the electrode rod, and a movable abutment member which operates automatically for partly closing the smaller end of said slot when the electrode rod is pushed through and moves out of said slot for the transverse passage 5 of said projecting electrode rod.
19. The invention claimed in claim 17 in which the said third plunger also compresses the depolarizing material in the mold around said electrode rod.
- 15 20. The invention claimed in claim 19 in combination with an automatically acting abutment member for partly closing said slot in the backing plate during the compression of the depolarizing material therein 20 and movable out of said slot for permitting the transverse passage of the projecting end of the electrode rod as the turret rotates relatively to said bottom-forming backing plate.
- 25 21. A bobbin making machine having, in combination, a mold, means for supplying depolarizing material to the mold, means for compressing and forming a hole in the depolarizing material in the mold, means for 30 inserting an electrode rod part way into the hole formed in the charge of depolarizing material, and means for further compressing

the depolarizing material and concurrently forcing said rod through such material until its opposite end projects therefrom. 35

22. The invention claimed in claim 2 in which the plunger for inserting the electrode rod is adapted to insert said rod only part way into the hole formed in the depolarizing material in the mold. 40

23. The invention claimed in claim 3 in which the plunger for inserting the electrode rod is adapted to insert said rod part way only into the hole in the depolarizing material in the mold. 45

24. The invention claimed in claim 4 in which the plunger for inserting the electrode rod is adapted to insert said rod part way only into the hole punched in the material in the mold. 50

25. The invention claimed in claim 5 in which the means for pushing the electrode rod into the hole in the charge of depolarizing material in the mold is adapted to push said rod part way only into such hole. 55

26. The invention claimed in claim 6 in which the means for pushing the electrode rod into the hole in the charge of depolarizing material in the mold is adapted to push said rod part way only into such hole. 60

In testimony whereof, we have affixed our signatures to this specification.

ABRAHAM KIPNISS.
MAX PAUL NEUMANN.
